Term of patent 14 years

Int. Cl. D23—01

U.S. Cl. D23—3

The figure is a perspective view taken from the front and top of a chlorinator unit showing my new design. The sides, bottom and rear of the chlorinator unit are plain and unornamented.

The characteristic feature of my design resides in the appearance of the front panel thereof.

I claim:

The ornamental design for a chlorinator unit, substantially as shown and described.
